UNITED STATES PATENT OFFICE.

JEAN KÜNTZIGER, HERMAN CHAUVIN, AND FÉLIX FONTAINE, OF LIEGE, BELGIUM.

CIRCUIT-BREAKER.

1,298,736.

Specification of Letters Patent.

Patented Apr. 1, 1919.

Application filed September 7, 1916. Serial No. 118,915

To all whom it may concern:

Be it known that we, JEAN KÜNTZIGER, HERMAN CHAUVIN, and FÉLIX FONTAINE, subjects of the Kingdom of Belgium, and residents of Liege, Belgium, have invented certain and useful Improvements in Circuit-Breakers; and we do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to a circuit-breaking device for continuous or alternating current. According to this invention the decrease of tensile strength of a wire, due to the heating effect of a current passing therethrough, is utilized to effect the rupture of an electric circuit. The wire is preferably arranged in the circuit to be controlled and is normally subjected to tension. As the wire is heated, its tensile strength diminishes and the tension thereon is ultimately sufficient to rupture the same and effect the breaking of the circuit.

It is to be noted that the working of such a circuit-breaker is quite different from the working of apparatus in which fuses are employed. The wire does not become warm under the normal conditions and the mechanical means stretching the wire is regulated in such a manner that so long as the intensity of the current passing through the wire has not reached a predetermined value, the tensile strength of the wire is sufficient to prevent its rupture and consequently the breaking of the circuit. As soon as the intensity of the current in the wire increases, the latter becomes warm, its tensile strength diminishes and at a determined temperature far below the melting point, the wire breaks and the circuit is consequently broken.

The desirable physical characteristics of the wire adapted to be traversed by the circuit to be broken, is found in standard steel wires used in the electrical industry for rotor wire binding, and also in bronze wires having the following composition: copper 87%, tin 8.7% and zinc 4.3%. Such a wire is a standard trade article in the metal industry.

Experiments have proved that when the intensity of current passing through such a wire exceeds a certain value, the tensile strength of the latter decreases rapidly in proportion to very small increase in the current; it is consequently possible to obtain in the working of the device a precision not attainable with fuse-devices. As the wire breaks at a temperature far below the melting-point the danger of the wire becoming melted is obviated. The metal of which the wire is made must be homogeneous, its tensile strength must be near its limit of elasticity and its elongation when breaking must be small.

The wire may be covered by a suitable sheath to prevent dissipation of heat and to protect it from exterior influences.

The wire may be traversed by the whole current or a portion of the current may be shunted therethrough. In the first case, the rupture of the wire directly effects the interruption of the current; in the other case, the rupture of the wire is adapted to cause the opening of a switch through which the main current passes.

When a shunt is used, the wire breaks without any sparking or arcing; however high the voltage may be; it is consequently not necessary to increase the length of the wire in order to prevent arcing when high voltages are used. Identical wires may therefore be used in various apparatus intended for different voltages or different intensities of current.

When the wire is shunted, it is easy to obtain as long a retardation in the working as may be required. It is therefore only necessary to construct the shunt of a metal whereof the resistance varies according to the temperature, said shunt being covered by a sheath which prevents any transmission of heat and effectively protects the same from exterior influences. In this way a circuit-breaker with retarded working is obtained, that is to say a circuit-breaker in which the circuit is only broken after a current of predetermined intensity has been transmitted for a certain time. Such a circuit-breaker does not possess the inconveniences of other circuit-breakers with retarded working in which an electro-magnet device is utilized in combination with relays, disengaging apparatus, clock-work or other similar devices. It is to be noted that the

length of time it takes the wire to effect the breaking of the circuit depends on the value of the coefficient of increase of the resistance of the metal of the shunt according to the increase of temperature, it being assumed that all other conditions remain unchanged.

The apparatus may be combined with a device allowing the wire to be replaced without necessity of employing a special circuit-breaker, but allowing the resetting of the apparatus only when the wire is stretched. If the current which has actuated the apparatus is still flowing, the latter will open again. These results are attained by securing one end of the wire to a lever which opens the main circuit as soon as it is displaced in order to put on a new wire. This lever may be the lever that opens automatically when the apparatus is put into action by the increase of intensity of the current (Figure 3) or another hand-operated lever (Fig. 4).

The accompanying drawings show, by way of example, different embodiments of the invention.

Figs. 1 and 2 show two embodiments in the case where the whole current passes through the wire to be ruptured, that is to say when the retardation in the working must be slight or practically *nil*, and principally in cases of low or moderate intensities.

Figs. 3 and 4 show two embodiments in the case when the wire is connected to the terminals of the shunt the resistance of which varies according to the temperature, said terminals being also connected with the ends of the circuit to be broken.

In the device of Fig. 1, the wire 1 is arranged in the axis of an insulating tube 2 located in an insulating block 3. This tube 2 is closed by means of two metal covers 4 and 5 electrically connected at 6 and 7 with the wires of the circuit. The wire 1 is secured at one end to the cover 4 and at the other end to a plate 7 actuated by a spring 8. The plate 7 is secured to a rod 9, and is connected by means of a flexible cable to the cover 5. Both ends of wire 1 are provided with a securing device in the form of a truncated cone 10 adapted to be introduced in housings of corresponding form provided in plate 7 and cover 4. In order to render it possible to put the wire in place, the plate 7 and cover 4 are provided with radial slits ending in the conical housing of each member. An insulating tube 11 is concentrically arranged around the wire 1 in order to prevent the broken wire from coming into contact with the spring 8.

If the current passing through the wire increases beyond the intensity corresponding to the diameter of the wire and the strength of spring 8, the wire becomes warm

and breaks, so that the circuit is broken. At the same moment, the rod is moved upward and gives warning on the outside that the wire is broken. When a new wire is to be inserted, the tube 2 is first taken out of the block 3, and the cover 5 and plate 7 removed by means of the rod 9. The head of the new wire may now be placed in plate 7, both plate 7 and wire 1 are again introduced into the tube 2, the rod 9 is then pushed down so that the wire 1 projects outward at the bottom of tube 2, the cover 4 having been withdrawn; the lower end of wire 1 is then introduced in the cover 4 and said cover is again put in place on tube 2. This manner of replacing the wire serves to prevent the use of a wire adapted to carry a current of greater intensity; it is therefore only necessary to make this latter wire shorter.

In the embodiment of Fig. 2, the wire 12 is stretched between the knife-blade 13 actuated in the direction of the arrow by a spring 14 and a knife-blade 15 pivotally mounted at 16 and closing at 17 the circuit formed by the members 13, 12, 15 and 17.

A spring-pawl 18 holds said knife-blade 15 in position. Both ends of wire 12 are provided with a securing device in the form of a truncated cone 55 adapted to be introduced in housings of corresponding form provided in the plates 56 and 57 secured to the blades 13 and 15 at right angles thereto; the narrow slits 58 cut in the plates 56 and 57 are intended to render it easy to put the wire in the right position. When the handle 59 is held in the closed position by the spring-pawl 18, the wire is stretched by the action of the spring 14.

When the wire has been broken owing to the increase of the intensity of the current and it is consequently necessary to change it for another one, the spring-pawl 18 is operated by means of a rod 19 and the knife-blade 15 is turned down by means of the handle 59; a new wire 12, provided with conical securing device as in the foregoing example, is put in place and the blade 15 is then brought again in engagement with the spring-pawl 18.

The apparatus of the Fig. 2 as well as apparatus of Figs. 3 and 4, may be opened quickly by actuating the spring-pawl holding the circuit-breaker closed.

In the embodiment illustrated in Fig. 3, the wire 20 is stretched between two knife-blades 21 and 22, which tend to turn in the direction of the arrow under the action of the springs 23 and 24. The main current passes through an element 30, the resistance of which varies according to the temperature; this main circuit is closed by the knife-blade 22 and the contact-blade 29.

A portion of the main current is shunted through the flexible wire 25, the knife-blade

21, the wire 20 and blade 22. The knife-blade 22 is normally held in the position shown in the drawings, by the spring-pawl 26. When the wire 20 breaks, the knife-blade 21 turns on its pivot and the nose 27 thereon actuates the rod 28 which in turn lifts the spring-pawl 26. The blade 22 is then allowed to turn under the action of the spring 24 and consequently interrupt the circuit.

In the embodiment illustrated in Fig. 4, the movable portion of the circuit-breaker comprises the two knife-blades 31 and 32 pivotally mounted respectively at 33 and 34 upon insulated brackets 35 and 36 fixed to the plate 37.

The knife-blade 31, which is integral with the handle 38, is brought into contact with the terminal 39 when it is pushed between the flexible jaws 40 connected to the said terminal 39. The knife-blade 32 is provided with brushes 41 adapted to contact with the blade 42 connected to the terminal 43; this blade is connected at 44 to a spring 45 which urges the blade to turn on its pivot 34, so as to separate the brushes 41 and the blade 42. The two knife-blades 31 and 32 are electrically connected together first by means of a shunt 46 of a metal the resistance of which varies according to the temperature, and also by means of a small wire 47 which when traversed by a current of increasing intensity causes the working of the apparatus.

The shunt 46 is connected with the blades 31 and 32 by the terminals 48 and 49 and the flexible wires 50 and 51. When the wire 47 breaks under the action of the spring 45, the blade 32 turns on its pivot 34, and the brushes 41 are quickly disengaged from the blade 42, so that the circuit is broken.

The blades 32 and 42 may be provided with metal strips 52 and 52' between which the breaking spark is produced.

When the apparatus is to be opened by hand, it is only necessary to actuate the handle 38 after having pushed the rod 53 of said handle so as to disengage the spring-pawl 54. The knife-blade 31 is then moved by the handle and the knife-blade 32 by the action of the spring 45.

It is to be noted that in such a circuit-breaker the resetting is prevented, since if the apparatus is again closed after the broken wire has been replaced, the circuit will be broken again if the overload in the

circuit is still existing, even if the operator holds the handle 38 in the closed position.

It is hardly necessary to mention that such an apparatus may be used for high tension or low tension currents. When high tension currents are used, it is advantageous to send into the apparatus, in lieu of the high tension current, a low tension current obtained by means of a transformer; the movements of the parts of the low tension apparatus are then mechanically transmitted to a suitable device adapted to interrupt the high tension current.

We claim:

1. In a circuit-breaker, the combination of an insulating tube closed by a metal bottom plate connected with one end of the circuit to be broken, and by a cap, a plate being adapted to move inside said tube; of means for connecting said movable plate with the other end of the circuit to be broken, a wire made of a metal having a high tensile strength and a limit of elasticity approximately coincident with the breaking point, with little elongation when breaking, means for securing one of the ends of said wire to the said base plate and the other end to the movable plate and a very strong spring tending to force the said plates apart.

2. In a circuit-breaker, the combination of an insulating tube closed by a metal bottom plate connected with one end of the circuit to be broken, and by a cap, a plate being adapted to move inside said tube: of means for connecting said movable plate with the other end of the circuit to be broken, a wire made of a metal having a high tensile strength and a limit of elasticity approximately coincident with the breaking point, with little elongation when breaking, means for securing one of the ends of said wire to the said base plate and the other end to the movable plate, a rod secured to the movable plate and passing freely through the cap to indicate outside the position of the movable plate within the tube; and a very strong spring tending to force the said plates apart.

In testimony whereof we affix our signatures in presence of two witnesses.
